APPARATUS FOR REVIVIFYING SPENT DE-COLORIZING MATERIALS

Carl G. Koepll, New York, N. Y., assignor of one-half to Anthony William Deller, New York, N. Y.

Application May 31, 1934, Serial No. 728,298

4 Claims. (Cl. 202—124)

The present invention relates to a process of revivifying spent decolorizing and/or purifying material, and more particularly to an improved method of roasting spent decolorizing and/or purifying material by indirect heat and to a new and improved apparatus therefor.

It is well known that heretofore decolorizing and purifying materials, such as clay, were used to decolorize and/or purify liquids, such as mineral oils, lubricating oils, gasoline, kerosene and the like. In this process clay or similar material absorbed and/or adsorbed contaminating substances which colored and which rendered the liquid impure. After the clay had been used for a period of time it was saturated with the contaminating substances and did not have any further power to decolorize and/or purify liquids, such as hydrocarbons or other organic liquids. It was then necessary to revivify the spent clay in order to make it useful for further treatments. Generally, the spent clay was fed to a furnace where it was heated by direct contact with hot gases and/or with direct contact with a flame from a burner. Thus, for instance, spent clay was fed to a roasting furnace of the Herreshoff or Wedge type through a feeder nozzle or other feeding device. The clay fell upon the top hearth of the multiple hearth furnace and was then carried from one hearth to a lower hearth by means of teeth or plows which were secured to rabble arms. As is well known these arms were secured to a single vertical shaft which extended through the center of the furnace from the top to the bottom and which was rotated in a suitable manner, such as by means of a set of gears connected to an electric motor. In other words, the clay in its downward travel through the multiple hearth furnace fell through ports located on the periphery of the "out-hearths" and through central ports on the "in-hearths".

Associated with each hearth or with alternate hearths or with special hearths, burners were provided by means of which the clay was heated and roasted by direct contact with the flame from the burner and by direct contact with the hot gas generated thereby. The direct impingement of the flame on the clay drove off the volatile compounds, such as hydrocarbons, and roasted the clay. The heat from the flame carbonized and burned out the coloring and contaminating substances which were contained in the pores of the clay. It has been found in connection with prior procedures that the clay has been subjected to temperatures which were so high as to cause calcining and sealing of the pores of the clay.

In burners of the multiple hearth type, it has been possible to observe zones of heating where the open flame of the burner directly impinges on the clay. In these prior procedures any hydrocarbon, such as naphtha, mineral oil, gasoline, kerosene and the like, were ignited and burned at the surface of the clay. The burning of these hydrocarbons increased the surface temperature and tended to sinter the clay and to convert at least a part thereof to a sintered condition. It is well known that the filtering efficiency of such clay has been very small.

Due to the draft pressure necessary to maintain combustion in ordinary multiple hearth furnaces (usually about 0.12 to 0.20 inch water pressure), stack losses as high as 20 to 30% of the clay were encountered and unfortunately the lost material invariably included more than its proportional part of the more active components of the absorbing material with the result that the recovered material was of greatly reduced efficiency. After each revivifying cycle or passage through the multiple hearth furnace, the filtering efficiency of the clay was steadily and rapidly reduced and finally was so low that the clay could not be used at a profit. Although many attempts were made to remedy the foregoing shortcomings, the proposals, as far as I am aware, only provided procedures wherein the clay could be used only a very few times before it had lost its absorbent and/or adsorbent properties and became practically valueless as a commercial decolorizing and purifying material.

I have discovered a procedure by means of which the shortcomings noted hereinabove can be avoided and by means of which spent decolorizing and/or purifying materials can be revivified efficiently without detrimentally affecting the decolorizing and purifying efficiency.

It is an object of the invention to provide a procedure involving the indirect heating of the spent decolorizing and/or purifying material and the isolation of the flame and heating gases from impinging directly upon, coming in contact with, contaminating the spent material under treatment and at the same time eliminating slack losses of fines, amounting to 20 to 30% of the clay.

It is another object of the invention to provide a process for indirectly heating and roasting spent material and to evaporate the volatile substances, such as oil, naphtha or the like, without detrimentally effecting such substances and without burning or contaminating them whereby the evaporated substance, such as oil, naphtha and

the like can be recovered as valuable by-products.

It is a further object of the invention to provide a process of indirectly heating and roasting spent decolorizing material and to transfer heat to said material at a high efficiency.

Another object of the invention is to provide an improved process for revivifying spent decolorizing materials in which the distillation of adsorbed hydrocarbons is effected without the aid of any 10 artificial inert atmospheres, steam, or products of combustion.

It is also an object of the invention to effect the oxidation of the carbonaceous matter to complete the revivification of the material after 15 distillation of hydrocarbon impurities by spontaneous combustion with air without sintering or otherwise impairing its decolorizing and purifying efficiency and without the presence of steam, or other additional inert atmospheres.

20 It is within the contemplation of the invention to provide an improved and simple apparatus for carrying the present invention into practice which has a combustion chamber to provide the heat necessary for the distillation of the adsorbed hydrocarbons, a zone of distillation associated 25 with and isolated from the combustion chamber to prevent the products of combustion from coming in contact with, and contaminating the products of distillation, and a zone of oxidation associated with, but substantially isolated from the zone of distillation to prevent the air from mixing 30 with the products of distillation.

Moreover, the invention contemplates providing an apparatus in which the material to be 35 treated flows by gravity in a substantially continuous manner, and which is capable of treating different materials simultaneously and independently from each other.

Other objects and advantages of the invention 40 will become apparent from the following description taken in conjunction with the accompanying drawings, in which:

Fig. 1 illustrates diagrammatically a vertical section of an apparatus embodying the present 45 invention and capable of carrying the present procedure into practice.

Figs. 2, 3, 4, and 5 are sectional views taken on lines 2—2, 3—3, 4—4 and 5—5, respectively, of Fig. 1.

50 Fig. 6 depicts an enlarged elevation view with parts broken away showing more in detail a zone of distillation and heat exchange devices near line 3—3 of Fig. 1.

Fig. 7 shows a perspective view with parts 55 broken away of a helical conveyor near line 4—4 of Fig. 1; and

Fig. 8 illustrates a perspective view with parts broken away of a water cooled helical conveyor near line 5—5 of Fig. 1.

60 In general, the apparatus shown in Fig. 1 comprises several zones, every one of which is so designed and controlled as to perform a certain function and to effect a certain desired result on the material to be treated. The zones are contiguous and superimposed sections of the apparatus which for purpose of illustration may be classified as the feeding zone, the preheating zone, the zone of distillation, the zone of oxidation, the cooling zone and the discharging zone.

70 In particular, the apparatus or furnace may be a fabricated steel structure comprising a plurality of vertical members 9 and cross members 10 welded or riveted together, in which other parts and sections of the apparatus are properly fitted and supported.

The charging zone comprises a plurality of charging hoppers 11, located over the upper end of the structure for the purpose of charging the clays or other materials to be treated into the apparatus. The material may be fed to hoppers 5 11 by any conventional charging device, not shown in the drawings, such as by automatic skips or bucket hoists, or it may be stored in stationary bins located over the hoppers and be released as required. The hoppers extend through 10 the roof of the apparatus into the preheating zone and feed the material to a plurality of inclined chutes 12.

The preheating zone, which constitutes the upper part of the apparatus, may be an insulated 15 or refractory lined chamber provided with a plurality of inclined stationary chutes 12. Chutes 12 convey the material to be treated from charging hopper 11 to ports 15 at the bottom of the chamber, and discharge over a plurality of helical, 20 or spirally wound stationary chutes 18 which extend vertically through the rest of the apparatus from the bottom of the preheating zone, and discharge into discharge hoppers 31 at the lower end of the apparatus. It is to be observed that chutes 25 12 and 18 provide direct paths for the material to be treated which are independent from one another and are capable of being charged and discharged separately, and in which the material flows by gravity alone. Ports 22 equipped with 30 doors 23 and peep holes 24, are provided in the sides as a means of inspection and of access into the preheating chamber. Reference character 13 designates outlets, preferably at the top of the apparatus, for the withdrawal of the products of 35 distillation from the preheating chamber and from the zone of distillation. In connection with outlets 13, it is preferred to have means, not shown in the drawings, for collecting and for condensing the products of distillation. Other 40 methods for conveying the material through the preheating chamber may be adopted, for instance, by extending helical chutes 18 upwardly to hoppers 11.

Directly under the preheating chamber is the 45 zone of distillation, which consists of a combustion chamber for supplying the heat necessary for the distillation, and of a plurality of vertical tubes 19 in which distillation and decomposition of substantially all the impurities in the material under treatment is effected. In order to prevent the products of combustion from contaminating the products of distillation, the combustion chamber is sealed from the adjacent zones and from the interior of tubes 19, and it divides the apparatus 50 except for tubes 19 which connect the upper preheating chamber to the lower chamber of oxidation and provides a passage for helical chutes 18. An effective way of sealing tubes 19 may be provided by flaring out and turning down the upper 55 ends of the tubes to fit lute rings 37 sunk into the upper surface of roof 14, while the lower ends of the tube fit into lute rings 38 sunk in the upper surface of bottom 39 of the combustion chamber.

In order to transmit the heat more efficiently 60 to the material under treatment traveling over chutes 18 in tubes 19, the tubes are preferably made to fit tightly over chutes 18 to provide actual metallic contact, and the outside surface of the tubes are provided with heat exchange 65 devices 20, which may consist of radiation fins, or a plurality of superimposed horizontal surfaces projecting from the sides of the tubes. Chutes 18 may also be constructed with the outside edges of the helical plates turned up at 70 75

right angles. This would increase the radiation contact surface between the tubes 19 and the chutes 18 and also prevent any clay from forming an insulation medium in case some of the clay may accumulate between the chute and the tube. Tubes 19 may be made of a heat resistant metal or of thermal refractory material, such as silicon carbide. Heat exchange devices 20 may be made of similar material and they may be fabricated as an integral part with tubes 19 or separately to fit over the tubes.

The combustion chamber may be fired by burners 25, for instance, of the tunnel type which confine the combustion of the fuel in tunnel 26 and convey the heat into the chamber by means of the hot gases of combustion. A more efficient and more uniform distribution of heat to all tubes 19 may be obtained and cold spots may be avoided by dividing the combustion chamber in three or more sections by means of baffles 41 extending horizontally across the chamber and having ports 42 for the products of combustion at alternate opposite ends of the sections. By placing burners 25 at one side of the lowest section of the combustion chamber, and outlet flue 27 at one side of the uppermost section, the products of combustion are made to flow horizontally in each section past all tubes 19, and the direction of flow is reversed in each successive upper section, until the outlet flue is reached. It is to be observed that besides equalizing the distribution of heat in tubes 19, baffles 41 also establish a temperature gradient which is opposite to the direction of flow of the material, the temperature being higher at the lower than at the upper end of tubes 19. Other sources of heat may, however, be adopted, as for instance by winding tubes 19 with electrically heated resistance wires, or by electric induction.

It is to be noted that the preheating chamber is supplied with heat from the combustion chamber by radiation through roof 14. A more efficient upward transfer of heat to the preheating chamber may be obtained by providing roof 14 with heat reflectors or ports 17 sealed by radiation plates 16, which may be made of any suitable heat resistant metal or of thermal refractory, such as silicon carbide. Ports 22 with doors 23 and peep-holes 24 are provided at the sides for the purpose of inspection or admission into the combustion chamber when repairs or replacement of parts are necessary.

Immediately below the combustion chamber lies the zone of oxidation which consists of an insulated chamber having a plurality of ports 21 at the top and a corresponding number of ports 39 at the bottom for helical chutes 18. The oxygen necessary for the burning out of the carbon, left on the material after the distillation treatment in tubes 19, is provided by circulating a suitable amount of air in the oxidation chamber through air inlet ports 28 at the bottom and large outlets 27 at the sides of the chamber near the top. The circulation of the air may be induced by any conventional method, and the amount may be controlled, for instance, by sliding valves 29 in inlet ports 28. It is to be observed that by restricting ports 21 at the bottom of tubes 19 to a size just sufficient for the free flowing of the material, and by making air outlet flues 27 sufficiently large, the velocity of the air is maintained at a relatively low figure, and the tendency for the air to rise to the upper parts of the apparatus above the oxidation chamber is practically eliminated. In traversing the oxida-

tion chamber, helical chutes 18 are not enclosed in tubes, but are preferably left open in order to provide free contact between the air and the material. Fig. 7 shows in detail the construction of chutes 18 in the oxidation chamber. It is observed that the material is prevented from falling off the chutes by having the outside edges of the helical plates turned up at right angle. The oxidation chamber is also provided at the sides with ports 22 to allow admission into the chamber when repairs or replacement of parts are necessary. Ports 22 are kept closed by doors 23 which are equipped with peep holes 24.

The cooling zone may consist of a plurality of tubes 30 enclosing spiral conveyors 18 and extending from ports 39 at the bottom of the oxidation chamber to hoppers 31 which may discharge the treated material to cars or to stationary bins, or to any other suitable device. A more rapid cooling of the material may be effected by circulating water, or any other cooling medium, inside the helical plates of chutes 18. Fig. 8 shows a preferred construction of the cooling plates. Water may be circulated through the cooling plates countercurrent to the downward flow of the material, for instance from manifold 32 connected to the lower end of the plates to water outlets 34 at the top. The total amount of cooling water may be controlled by valve 36 in the manifold line, or it may be controlled independently in any cooling plate by valves 35 in outlet water pipes 34.

In carrying out the present invention into practice, the material to be treated is fed to the furnace through hoppers 11, whereby it flows by gravity on chutes 12 through the preheating chamber and on helical chutes 18 downwardly through the rest of the apparatus to discharge hoppers 31. The flow of the material under treatment is continuous and is such that the process is substantially under control throughout the various stages of the operation.

In flowing through the preheating zone, the material is heated by heat radiating through the roof of the combustion chamber and is suitably prepared so that it may be acted upon more readily without tending to unduly cool down the next zone, or the zone of oxidation. Some of the lighter oils, such as naphtha may also begin to volatilize in the preheating chamber.

Active distillation and decomposition of substantially all the impurities adsorbed by the clays, however, occurs while the material flows through tubes 19. The naphtha and the lighter oil are first removed by distillation at the upper parts of the tubes, flow upwardly into the preheating chamber, and are recovered via outlets 13. In progressing further down towards the lower end of the tubes, the material is progressively heated to higher temperatures, and the heavier hydrocarbons, such as asphaltic and bituminous matter, are decomposed and distilled off leaving a carbon deposit on the particles composing the material. The lighter products of distillation flow upwardly and pass into the preheating chamber whence they are also withdrawn via outlet 13 to an appropriate recovery system for the recovery of naphtha, oils and the other vapors. The height and the temperature of the zone of distillation are so controlled as to effect the distillation of substantially all the hydrocarbon impurities in the material under treatment, without, however, dehydrating or causing the loss of the combined water of the material itself. It is to be observed from the construction of the apparatus

that the highest temperature is maintained at the lower end of tubes 19 in which active distillation takes place and that the temperature gradually decreases upwardly towards the preheating chamber, thus establishing a thermal gradient opposite to the flow of the material. The temperature of the lower end of tubes 19 is preferably kept at approximately 950°-1000° F. for new clays (second to fifth burns), and approximately 1000°-1050° F. for clays which have been treated several times. The temperature of the upper part of tubes 19 is kept at about 300° F., while the preheating chamber is maintained at a sufficiently high temperature to avoid the condensation of the products of distillation. If desired, thermostatic devices may be employed to maintain any selected temperature in the combustion chamber, spirals, etc.

When entering the oxidation chamber, the material consists of hot particles from which the adsorbed hydrocarbons have been substantially removed by distillation, but which are covered with carbon resulting from the decomposition of some of the heavier hydrocarbons. The temperature, however, is sufficiently high, about 1000° F. to cause the carbonaceous matter to ignite spontaneously, and to be burned out when the particles come in contact with the air flowing upwardly from air inlet ports 28. Any hydrocarbons which were not distilled off in tubes 19 are also burned out in the oxidation chamber by combining with the oxygen of the air. It is to be observed that the rate of combustion of the carbonaceous matter is high, but since the initial temperature of the particles is not very high, about 1000° F., and since the particles are moving towards an increasingly cooler zone, and against a counter-current flow of cold air, any excessive rise in temperature tending to cause fusion or dehydration of the particles is substantially prevented. The rate of burning of carbon may further be controlled by controlling the amount of air flowing in the oxidation chamber.

The residual air and the products of combustion of the carbonaceous matter are withdrawn through outlet flues 27 which are sufficiently large to keep the velocity of the air at a relatively low value, thereby preventing the gases from entering tubes 19 and contaminating the products of distillation.

In flowing through tubes 30, the material may finally be cooled down to any desired temperature by controlling the flow of water in the cooling plates, so that it may be conveniently handled when discharged by hoppers 31.

It is to be observed from the foregoing description that the invention affords an improved, rapid and efficient method for the revivification of spent decolorizing material used in the refining of mineral oils, or the like, in which the distillation of the adsorbed hydrocarbons is carried out without the aid of any artificial inert atmospheres, or of steam, and without contamination by the products of combustion. The naphtha and the other products of distillation are recovered in a substantially pure state and with practically little losses, while after treatment by the invented process the material has retained substantially intact its cellular structure free from adsorbed matter or carbon of decomposition, and its adsorptive properties have been practically restored. The material moves through the apparatus by gravity alone without the aid of any external motive power, and in a steady stream like the flow of a fluid material. The material

cannot accumulate at any stage of the process, and in following a tortuous path is continually turned over exposing fresh parts to be acted upon, thereby insuring a more uniform and more rapid treatment of all its parts.

It is also to be observed that the invention provides an improved apparatus in which the process is carried out in a very rapid, efficient and economical manner. Special features of the apparatus are its simplicity of construction, the absence of any moving parts, and its flexibility of operation, which enables it to treat different materials simultaneously and independently from each other. The capacity of the apparatus can easily be increased by extending one side to include an additional number of separate chutes or paths for the material or, if desired, can be extended vertically.

Although the present invention has been described in connection with the revivification of 20 clays, it is to be understood that other materials may be treated and that a great variety of chemical and metallurgical procedures may be conducted in the furnace. As those skilled in the art will readily understand, modifications 25 and variations may be resorted to without departing from the spirit and scope of the invention. Thus, for instance, the apparatus may be used for the regeneration of sugar house, bone black, activated carbon, charcoal, etc., or for 30 the calcining of limestone, whereby burnt lime is produced and carbon dioxide is recovered in a substantially pure condition. It is understood that when treating a substance such as limestone from which volatilizable substances may 35 be removed without leaving a residue of oxidizable products of decomposition, the oxidation chamber may be omitted from the construction of the apparatus and the cooling zone may be made to extend up to the heating zone thereof. 40 Then again movable screws can be provided instead of stationary helices, or conical tubes may be used instead of cylindrical ones.

I claim: —

1. An apparatus for revivifying spent decolorizing materials comprising a plurality of vertical stationary conveyors conveying the material under treatment through the apparatus, means for feeding said material to the upper end of said conveyors, a metallic tube of high heat conductivity for each of said conveyors surrounding the upper portion thereof, means for collectively heating the outer surface of said tubes to cause indirect heating of the material within said tubes and to volatilize volatilizable substances therefrom, means for withdrawing said volatilized substances free from products of combustion, means for flowing air around an intermediate portion of said conveyors at a level lower than said tubes to cause combustion of carbonaceous substances in said material, and means for cooling the lower portion of said conveyors to cool the revivified material before discharging.

2. An apparatus for revivifying spent decolorizing materials comprising a plurality of vertical stationary helical chutes for conveying the material to be treated through the apparatus under the action of gravity, a metallic tube of high heat conductivity for each of said chutes surrounding the upper portion thereof, means for heating the outer surface of said tubes to cause indirect heating of the material within said tubes and to volatilize volatilizable substances therefrom, means for isolating said heated portion of said chutes from the products of 75

combustion derived from said means for heating, means for withdrawing said volatilized substances free from products of combustion, means for exposing an intermediate portion of said 5 chutes to air to cause combustion of carbonaceous substances contained in the material, and means for cooling the lower portion of said chutes to cool the treated material before discharging.

3. An apparatus for revivifying spent decolorizing materials comprising a plurality of vertical stationary helical chutes for conveying material to be treated through the apparatus, a heat exchange tube for each of said chutes enclosing the upper portion thereof, a combustion 10 chamber surrounding said tubes to indirectly heat material on said chutes and within said tubes, means for withdrawing volatilized substances from said tubes free from products of combustion, an oxidation chamber underlying the 15 combustion chamber and directly surrounding an intermediate portion of said chutes, means for isolating said oxidation chamber from the combustion chamber, means for admitting air into the oxidation chamber to cause combustion 20 of carbonaceous substances in said material, and means for cooling the lower end of said chutes to cool the revivified material before discharging.

4. An apparatus for revivifying spent decol-

orizing materials comprising a plurality of vertical stationary helical chutes for conveying the material to be treated through the apparatus under the action of gravity, means for separately feeding and discharging said chutes, a combustion chamber enclosing an upper portion of said chutes, means including a heat transfer tube around each of said chutes for isolating said upper portion of the chutes from the combustion chamber and for transferring heat efficiently 10 and uniformly to the material on the heated portion of said chutes, means for withdrawing volatilized substances free from products of combustion, an oxidation chamber underlying the combustion chamber and surrounding an intermediate portion of said vertical chutes, means for isolating said oxidation chamber from the combustion chamber, means for admitting air into the oxidation chamber to cause an air current flowing in a direction opposite to the flow of the 15 material, means for controlling said flow of air, means for withdrawing the products of oxidation without substantially contaminating the volatilized substances, and means for cooling the lower portion of said chutes to cool the revivi- 20 25 fied material before discharging.

CARL G. KOEPLI
